UNITED STATES PATENT OFFICE.

WILLIAM D. GRIMSHAW, OF NEW YORK, N. Y.

IMPROVEMENT IN POWER-THERMOMETERS.

Specification forming part of Letters Patent No. **222,897**, dated December 23, 1879; application filed October 30, 1879.

To all whom it may concern:

Be it known that I, WILLIAM D. GRIMSHAW, of the city, county, and State of New York, have invented a new and useful Improvement in Power-Thermometers, which invention is fully set forth in the following specification, reference being had to the accompanying drawings, in which—

Figure 1 represents a front elevation, partly in section, of my thermometer. Fig. 2 is a vertical cross-section thereof.

Similar letters indicate corresponding parts.

My invention relates to the construction of thermometers with the view of obtaining power; and it consists in the combination of a series of air-tight chambers having elastic heads and connected side by side at their centers, a rack-bar projecting from the outer head of one of said chambers, a shaft provided with means for transmitting motion and carrying a pinion meshing with said rack-bar, a pointer projecting radially from said shaft, and a graduated scale arranged adjacent to said pointer.

The expansion of the heads of the chambers causes the rack-bar to turn the shaft, and from said shaft motion is communicated to a damper or other movable device, while the pointer indicates the degree of heat at which this action takes place.

In the drawings, the letters A A' designate two closed vessels, which are filled with air of the same pressure as the external air, or with any other fluid, and constructed with elastic heads B B'. These vessels A A' are metallic, and have circular shapes, while their heads B B' are rendered elastic by means of concentric corrugations formed therein, as shown in Fig. 2. Said vessels A A', moreover, are connected together at the center by a hollow joint, a, the same being situated one above the other, and the lower vessel, A', is connected to a base, C, by means of a central hollow joint, b.

When the temperature of the air or other fluid in which my thermometer is placed rises or falls, it follows that a like effect is produced on the air or fluid contained in the sealed vessels A A', and as the inclosed air expands or condenses it acts upon the elastic heads B B', with a tendency to cause these heads to rise and fall, which they are capable of doing by reason of their elasticity.

By the arrangement of the two vessels A A'

the heads of one vessel act upon those of the other vessel and displace the latter; but I do not wish to be restricted to the use of two vessels.

For the purpose of steadyng the vessels A A' springs or cushions c are interposed between the upper vessel and a suitable part of the thermometer-frame.

The letter D designates a rock-shaft, which receives motion from the heads of the vessels A A' as the same rise or fall, as before stated, so that a certain amount of power may be obtained from the rock-shaft. To this end I connect the rock-shaft D with the upper head, B, of the vessel A, using a rack and pinion, d e, for this purpose.

On the rock-shaft D may be mounted a pulley or other device, for connecting the same with a ventilator in an apartment, or with a damper or valve upon a heating apparatus.

The letter E designates an index-hand, secured to the rock-shaft D, and F a scale adapted to the index-hand. This scale F is secured to the thermometer-frame, and consists of a strip of sheet metal marked with suitable characters, and arranged concentric to the shaft D.

It will be readily perceived that by the index-hand and scale the temperature of a fluid, as the air in an apartment, is indicated.

I am aware that sealed vessels with elastic heads exhausted of air have been used for indicating atmospheric pressures, and such not being within the scope of my invention, I hereby disclaim the same.

What I claim as new, and desire to secure by Letters Patent, is—

The combination of the air-tight chambers A A', having the elastic heads and connected at the centers of their contiguous heads, the rack-bar projecting from the center of the head of one of the said chambers, the shaft D, provided with a device for transmitting motion and carrying the pinion e, meshing with said rack-bar, the indicator E, carried by said shaft, and the graduated scale F, substantially as and for the purpose set forth.

In testimony that I claim the foregoing I have hereunto set my hand and seal this 28th day of October, 1879.

W. D. GRIMSHAW. [L. S.]
